 land, Ohio, a corporation of Delaware

Application February 17, 1945, Serial No. 578,507

7 Claims. (Cl. 235—61.9)

1

This invention relates to printing machines and particularly to printing machines adapted for use in accounting work to produce accounting records and the like.

In the preparation of accounting records, situations often arise wherein it is desirable to perform posting operations in respect to a large number of accounts and in such instances it is desirable to verify the accounting operation through the accumulation of totals of the amounts that are thus posted upon the records that are prepared. One situation where such posting operations are to be performed arises where at least certain of the persons included on a relatively large payroll have authorized the making of deductions of varying amounts from the sum that would be due to such persons for each payroll period. Thus, for example, a person that is included on a payroll may authorize the deduction of a particular amount from his monthly pay, and may give instructions as to the disposal of the amount that is thus deducted, and in such an instance it is customary to prepare an accounting record in respect to each such authorized deduction so that the making of the deduction for each regular pay period may be recorded or posted upon such record, and to enable this to be accomplished accurately and rapidly is the primary object of the present invention. A further and related object of the invention is to enable records in respect to payroll deductions and the like to be rapidly and accurately printed while the amounts of such deductions are accumulated by an accumulator that forms part of the machine that performs the posting operation.

A further object of the invention is to enable each record card to carry representations of the amount that is to be deducted or posted on such card for each regular posting or pay period, and to enable accumulation of the posted amounts to be accomplished as a incident to the actual posting operation that is performed with respect to each card. Objects related to the foregoing are to enable the amount represented in such a record or card to be sensed at the same time when the posting of the card is accomplished, and to accomplish both of these operations at a single working or operating station so as to thereby require but a single stopping of the card in order to perform these two operations.

A further object of the invention is to simplify the posting of records, and more specifically it is an object of the invention to enable a posting unit for operating on such cards to be so con-

2

structed and arranged that it may be readily set in different positions so as to accomplish the posting operation in different areas of the cards or records in accordance with the setting of the posting unit.

Where data representations are afforded in a sheet or record card and where such representations are to be sensed while a posting operation is performed on another portion of the sheet or record card, the area of the card that is to be sensed for determining the value of the data representations will remain the same in each use of the cards and the machine, but the posting operations will be performed on different portions or areas of the cards in each successive run of the machine, and in accordance with the present invention the posting means or posting unit is mounted in different positions to attain such different locations of the posting impressions, and it is a further object of the present invention to enable such a posting unit to be operated in a manner that facilitates such shiftable mounting of the posting unit. A more specific object of the invention is to operate the posting unit of the apparatus through a Bowden cable connected from the sensing means, thereby to cause operation of the posting unit each time the sensing means are operated through a sensing cycle.

Where amounts are represented in a record or card so as to enable these amounts to be sensed and accumulated, it is essential that each record card be accurately located in respect to the sensing means, and to enable this to be accomplished in a simple expeditious manner is still another object of the invention. Other and related objects of the invention are to so construct and relate the elements of a sheet or card feeding mechanism that the card may be advanced along a sheet guideway to an operating position and may thereafter be shifted in a lateral direction so as to attain accurate location of the card in such operating position. A further and more specific object is to embody jogging means in a card feed mechanism and to operate this jogging means so as to impart lateral shifting movement to each sheet or card as the card comes to rest in the operating position of the machine, and a more specific object

of the invention is to afford stop finger mechanism and jogging mechanism in such a machine and to operate these two mechanisms from the same operating cam shaft.

Other and further objects of the present invention will be apparent from the following de-

3

scription and claims and are illustrated in the accompanying drawings which, by way of illustration, show a preferred embodiment and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

In the drawings:

Fig. 11 is an enlarged view of the automatic total control mechanism as viewed from the right in Fig. 10 and showing certain electrical elements of the machine in diagrammatic association therewith.

Fig. 12 is a view illustrating the positional code whereby numerical amounts are represented upon the record cards that are used with the present embodiment of the machine; and

Fig. 13 is a front face view of a record card that is adapted to be operated upon by the present machine.

In the form chosen for disclosure herein, the invention is embodied in an accounting apparatus embodying a printing machine 10 having an adding unit 11 operatively associated therewith, and this apparatus is adapted to operate upon and under control of record cards C such as the card shown in detail in Fig. 13 of the drawings. The record card C is of substantially rectangular form, and has a posting area 15 thereon that is divided into a relatively large number of spaces in which records may be made. The record card C that is herein shown is particularly adapted and intended for the posting of amounts that are to be paid monthly, and the system of accounting for which the card C is intended contemplates that this amount will remain the same for each month of the year. Thus the card C has a posting area 15 provided thereon which is divided into a plurality of columns 16, each of which is divided into 12 line spaces 17 that are allocated one to each of the months of the

5

year. The month of the year to which each of the horizontal lines or spaces pertains is printed in a column 18 opposite the respective spaces or lines of spaces 17. Thus a particular column 16 may be allocated to a particular year, and the year to which a column 16 is allocated may be written or printed at the head of the column as at 19. Since it is contemplated that the deduction or amount that is to be posted monthly on the card C will remain the same, this amount is written or printed in words as at 20, and in figures as at 21, on the face of the card, and the fact of payment, for a particular month, of the amount that is thus written on the card is posted on the card merely by printing the word "Paid" as at 22 in the related space 17 of the proper column 16 of the card.

When posting operations are performed in this manner in respect to a series of cards C, it is desirable for accounting purposes that the amounts of the deductions that are thus posted on the series of cards be accumulated, and to accomplish this, the amount that is written or printed on the card C as at 20 and 21 is also represented on the card C by physical means such as coded perforations 25 that are in the present instance formed in the card in a field disposed near the upper left-hand corner portion of the card C as shown in Fig. 13. Such perforations are, in the present instance, formed in accordance with the positional code that is illustrated in Fig. 12 of the drawings, and it will be observed that this positional code includes five index points or positions. The makeup of the card C as herein shown contemplates the writing or printing of information such as a name 26A in the space between the two dotted lines 26 as shown in Fig. 13, and since this space extends across the field in which the coded perforations 25 are to be formed, the lower two lines of the positional code are spaced from the third line of the code in an amount sufficient to insure that such clear and unperforated space will be afforded in every instance on the card C between the lines 26. The field in which the numerical amounts are thus represented on the card C is of course arranged so that the digits of the numerical amount will be represented, order by order, in predetermined columnar locations that are related to an end 27 of the card in a particular and predetermined manner. The lines of the code in which the perforation as 28 are formed are also related to one of the longer edges of the card such as the edge 29, and when a card C is being punched to represent a numerical amount, or when the represented amount is being sensed, the location or positioning of the card C is determined by the edges 27 and 29 of the card.

60 The printing machine 10 of the present invention embodies a frame 35 having a table top T with a sheet guideway G extended-longitudinally along the table top so that sheets or cards such as the card C may be fed longitudinally along the table top T in the sheet guideway G. The sheets or cards C are fed one by one into one end of the guideway G by a sheet separating and feeding mechanism 31 that may be of the character shown in Gollwitzer Patent No. 2,002,773, patented May 28, 1935, or which may be of the kind shown in Gollwitzer Patent No. 2,342,190, patented February 22, 1944. When a sheet or card C is thus discharged into the right-hand end of the sheet guideway G, Figs. 1 and 2 of the drawings, the sheet is advanced along the sheet guideway by a

constantly operating feed belt 38 that may be mounted and driven in the manner described in Gollwitzer Patent No. 2,002,772, patented May 28, 1935. In its principal elements, the machine 10 of the present invention is constructed and arranged in substantially the manner described in the last mentioned Gollwitzer patent, with the exception however that the mechanism for advancing printing devices through the machine of said last mentioned Gollwitzer patent have been eliminated in the machine of the present invention, and the platen that was utilized in said last mentioned Gollwitzer patent has been eliminated and the platen supporting frame has been utilized for other purposes. Thus in the machine 10 of the present invention, a main shaft 40 is driven from a constantly operated flywheel 41 by clutch means of the one-revolution type that are under control of a main starting lever 42 and a stop lever 43. The starting lever 42 corresponds to the start lever 290 of the aforesaid Gollwitzer Patent No. 2,002,772, while the stop lever 43 of the present machine corresponds to the stop lever 304 of the last mentioned patent. When the start lever 42 is moved in a counterclockwise direction to the position shown in Fig. 1 of the drawings, the associated clutch means are engaged and are latched in such engaged relationship, and as described in the aforesaid Gollwitzer Patent No. 2,002,772, this drives the timing shaft of the sheet separating and feeding means 37 in timed relation to the main shaft 40 and a stop finger cam shaft 44 that extends along the rear portion of the frame above the table top T as will be evident in Figs. 1 and 2 of the drawings.

In the present machine, as described in said Gollwitzer Patent No. 2,002,772, the sheet or card is fed by the feeding means 37 in such a timed relationship that a sheet or card is located in the operating position during the last part of the machine cycle, and the sheet or card comes to rest in this position a substantial time before the end of the machine cycle. When a sheet or card C has been discharged into the sheet guideway G by the sheet separating and feeding means 37, this card is faced upwardly in the relationship shown in Fig. 13, and the edge 27 of the card constitutes the leading edge. This locates the side edge 29 of the card within an undercut groove 46 of a stationary rear rail member 47 that constitutes the rear member of the sheet guideway G, while the other or forward edge of the card is disposed in an undercut groove 48 of a stationary forward rail 49 that constitutes the forward edge of the sheet guideway G. The rear side of the sheet guideway G is in the present instance afforded by the member 47 and by another member 47A that are separately formed and are secured in stationary positions on the table top T by screws 50, and the forward edge of the sheet guideway is also defined by a plurality of members including the stationary rail member 49. Thus the forward edge of the sheet guideway includes a laterally shiftable guide member 55 that is disposed in substantial alignment with the stationary member 49, and at the left-hand end of the shiftable member 55, as viewed in Fig. 2, and a second stationary rail member 49A is disposed so as to form a continuation of the forward edge portion of the sheet guideway G. When a card C reaches a position opposite the shiftable member 55, it is brought to rest in an operating position by a stop finger 60 that is adapted to be moved from an upper or ineffective position into a lower or effective position

wherein it is disposed in the path of the leading edge 27 of the card C. When the card C is in the operating position that is thus defined, the perforations 25 of the card are disposed in position for cooperation with sensing mechanism 70, while the posting area 15 is disposed in position for cooperation with a posting unit 80 that operates to print the word "Paid" as at 22 on the card C.

The advancing movement of the card C along the sheet guideway G is attained by frictional contact of the card with the constantly moving belt 38, and this frictional contact assured by a plurality of pressure rollers 73 that are resiliently mounted so as to bear against the upper faces of the cards C to press the same into engagement with the belt 38. As herein shown the stop finger 60 comprises a plate 61 disposed transversely of the sheet guideway G and pivoted by a mounting stud 62 on the forward end of an arm 63 that is in turn pivoted on a supporting shaft 64. The arm 63 extends rearwardly from the shaft 64 and has a roller 65 disposed as a cam follower beneath the edge of a stop finger cam 66 mounted on the stop finger cam shaft 44. It will be observed that the stop finger plate 61 has a slot 67 cut in its lower edge so as to afford clearance for the belt 38, and when the stop finger plate 61 is dropped to its lower position by the action of the cam 66, the edge 27 of the card C will move into abutment with the adjacent face of the plate 61 so as to be held in the operating position beneath the sensing means 70 and the posting unit 80.

It is important that the perforations 25 in the card C be accurately located with relation to the sensing means 70, and this is accomplished through the cooperative action of the stop finger 60 and a jogging mechanism that includes the shiftable member 55 of the sheet guideway G. In accomplishing this positioning action, the shiftable member 55 is mounted for shifting movement on supporting means that are in the nature of a parallelogram so as to maintain the shiftable member 55 parallel to the opposite member 47A of the sheet guideway at all times. Thus the rail member 49A of the forward side portion of the sheet guideway G has a forwardly projecting mounting arm 90 provided thereon upon which a pair of parallel bars 91 are pivoted as at 92, and these bars 91 extend in parallel relation along the member 49A and are pivoted in their other ends on a mounting arm 93 by pivots 94. The mounting arm 93 is formed on the shiftable rail member 55 so as to extend forwardly therefrom, and hence the member 55 may be shifted along a path that is perpendicular to the sheet guideway, and the member 55 in such shifting movement is maintained parallel to the member 47A of the sheet guideway at all times.

When a card C moves from its position between the members 47 and 49 and into position between the members 47A and 55, such movement is facilitated by an enlarged and tapered throat portion 95 formed at the right-hand end of the rail member 55, and after the card has progressed along the guideway and has been stopped by the engagement of its leading edge with the stop finger 60, a rearward jogging movement is imparted to the shiftable member 55 so as to engage the edge 29 of the card C with the member 47A and thereby accurately locate the card C in the desired operating position. Such movement of the shiftable member 55 is imparted thereto under the control of cam means mounted on the stop finger

cam shaft 44. Thus, as shown in Figs. 1, 2 and 3, an upstanding bracket 98 is provided on one of the arms 91 near the midpoint thereof, and a connecting link 100, including an adjustable turnbuckle 100A, has its forward end pivotally connected to the bracket 98. The rear end of the link 100 is pivoted to the upper end of a lever 101 which carries a cam roller 102 that bears against the forward edge of a cam 103 mounted on the cam shaft 44. The lever 101 is pivoted at 104 beneath the table top T, Fig. 3, and a forward extension 101A of the arm 101 has a spring 106 acting thereon so as to maintain the cam roller 102 in engagement with the cam 103. It will be observed in Fig. 3 of the drawings that the major portion of the cam 103 constitutes a dwell surface, and that a receding surface 103A is provided on the cam so as to allow rearward movement of the cam roller 102 and the link 100 late in the cycle of operation of the machine and after the sheet or card has come to rest at the stop finger 60. Thus, the cam 103 acts to maintain the shiftable member 55 in a forward position throughout most of the cycle of operation of the machine, but after a card C has engaged the stop finger 60, the receding surface 103A of the cam 103 causes the member 55 to be shifted in a rearward direction, thereby to engage the edge 29 of the card C with the rear side of the sheet guideway. Thus the edges 27 and 29 of the card C are accurately positioned so as to thereby accurately locate the card C in the desired relationship with respect to the sensing means 70 and the posting unit 80.

When the card C has thus been stopped and accurately located in the operating position, the machine operates in the next cycle thereof to effect the desired sensing and posting operations, and the numerical amount that is represented by the perforations 25 is sensed by the sensing means 70, and the word "Paid" is printed at the same time in the appropriate space 17 of the card C by the posting unit 80. The sensing means 70 are in the present instance carried by a rocker 105 that corresponds in form with the platen supporting casting 77 of the aforesaid Gollwitzer Patent No. 2,002,772, this rocker arm 105 in the present machine having cam rollers 106 thereon that are engaged by appropriate cams 107 mounted on the shaft 40 and cooperating with the cam rollers 106 so as to actuate the rocker arm 105 in a downward direction each time the shaft 40 is rotated. The downward movement of the rocker arm 105 takes place in each cycle of operation of the machine at the time when the card C is located at rest in the operating position as defined by the stop finger 60, and the downward movement of the rocker arm 105 is utilized in the present instance to effect downward sensing movement of the sensing means 70. The construction of the sensing means 70 is shown in detail in Figs. 3 to 7 of the drawings. Thus the rocker arm 105 has a casting 110 extended from its forward edge and this casting has mounting means thereon whereby a supporting plate 111 is secured in an adjustable position beneath the outer end of the casting 110. The mounting plate 111, as shown in Figs. 4 and 5, is supported by a headed bolt 112 that is extended through a bore 112A in the outer web portion 110A of the casting 110, and the lower end portion of this bolt is threaded through the mounting plate 111. The mounting plate 111 also has positioning and adjusting means interposed between the plate and the casting 110 on opposite sides of the support-

ing bolt 112, and as shown in Fig. 5, the web portion 110A has enlarged hubs 113 formed at the opposite ends thereof, these hubs having screw threaded openings extended downwardly therethrough. In each of the openings that are thus formed in the hubs 113, an adjusting screw 114 is mounted, each adjusting screw having a flange 115 near its lower end that rests on the upper face of the mounting plate 111. Beneath the flange 115, each adjusting screw has a pointed lower end 116 that extends into a bore 117 in the mounting plate. Thus, by adjustment of the screws 114, the mounting plate 111 may be rocked so as to bring the plate into a level relationship with respect to the table top T, and such an adjusted relationship may be maintained by tightening of lock nuts 118 that are disposed on the screws 114 in such positions that they may be locked against the lower faces of the hubs 113.

The mounting plate 111 serves to support and locate a pin box 120 in which a plurality of sensing pins 121 are mounted for vertical movement in positions for cooperation with the coded openings 25 formed in the cards C. The sensing pins 121 are mounted and guided for sliding movement in a pair of spaced plates 123 and 124 that are secured respectively against the upper and lower faces of the mounting plate 111 by a cap screw 125, and the plates 123 and 124 are held against rotation about the axis of the cap screw 125 by pins 126 that are fixed on the plate 123 so as to extend into aligned openings 127 formed in the upper plate 123 and the mounting plate 111. The plates 123 and 124 extend beyond one end of the mounting bar 111 and are maintained in spaced relationship by spacer studs 130 that are riveted at their lower ends at 131 to the lower plate 124 and which have the upper plate 123 held thereon by cap screws 132 extended through the upper plate 123 and threaded into the spacer studs 130. The sensing pins 121 are extended through aligned apertures in the upper and lower plates 123 and 124, and each sensing pin has a flange 134 formed thereon by means of a washer that is fixed thereto so as to engage the upper face of the plate 124 and thereby limit downward movement of the sensing pin. Each of the sensing pins 121 has an expansive coil spring mounted in surrounding relation thereto so that the upper end of the spring bears against the lower face of the plate 123 while the lower end of the spring acts against the flange 134 of the pin. Thus the sensing pins 121 are yieldingly urged in a downward direction toward the projected relationship shown in Fig. 5, and whenever a sensing pin 121 is in alignment with an opening or perforation 25 in a card C, this sensing pin will enter such perforation and pass therethrough as will hereinafter be described in detail. When, however, such a sensing pin 121 encounters an imperforate area of the card C, the sensing pin will remain in a stationary relationship as downward movement of the sensing means continues, and when this occurs the spring 135 that is associated with this sensing pin will, of course, be compressed. In the assembled machine the pin box 120 is enclosed and protected by a box-like housing 70A that surrounds and protects the top as well as the ends and forward side of the pin box. At its rear edge the housing 70A has an upwardly extending flange 136 that is secured to the forward face of the rocker 105 by cap screws 137.

The sensing pins 121 are disposed in positions wherein they are adapted to cooperate with con-

trol means for setting up the adding machine 11, and in the present embodiment of the invention, such control means are in the form of a plurality of Bowden cables 140, as shown in Figs. 3, 5 and 6. The Bowden cables 140 have sheaths 141, and are extended to the setup mechanism of the adding machine 11 in the manner that is explained in detail in my copending application Serial No. 676,329, filed June 12, 1946, now Patent No. 2,501,444 issued March 21, 1950. The ends of the Bowden cables 140 that are to be actuated by the sensing pins 121 are arranged, as shown in Figs. 3, 5 and 6, in association with a plurality of operating plungers 145 that are mounted for vertical movement in a mounting block 146, and the disposal of the actuating plungers 145 in the mounting block 146 is of course such that one actuating plunger 145 is disposed in position for cooperation with each of the respective sensing pins 121. As shown in Figs. 5 and 6, the mounting block 146 is secured beneath the table top T so that a portion 146A thereof extends upwardly through an opening in the table top T, and such mounting is in the present instance attained by a plurality of screws 146 extended downwardly through the table top and threaded into the block 146. Each actuating plunger 145 has a flange or head 145A at its lower end, and is mounted in an appropriately positioned bore 148 formed in the mounting block 146. Thus the abutment of the flange or head 145A of a pin with the lower face of the mounting block 146 serves to limit upward movement of the actuating plunger, and this relationship is such that each pin extends for a very slight distance above the upper face of the mounting block 146. The lower end of each of the plungers 145 has an axial bore formed therein, and the end of the Bowden cable 140 that is to be associated therewith is reduced, as will be evident in Fig. 6, so that this reduced end may extend into the bore formed in the lower end of the plunger 145. Thus the plunger 145 abuts a shoulder formed at the lower end of the reduced portion of the Bowden wire 140, and this relationship enables a downward movement that is imparted to the plunger 145 to be transmitted to the Bowden wire 140. The sheaths 141 of the Bowden wires 140 are extended through an anchoring plate 150 and are secured thereto as by soldering, and this anchoring plate is secured to the mounting block 146 by connecting screws 151 and spacer sleeves 152, as shown in Fig. 6 of the drawings. Thus when the pin box 120 of the sensing means is moved downwardly, any one of the sensing pins 121 that is aligned with a perforation in a card C may pass through such perforation and impart downward movement to the aligned actuating plunger 145. This movement of the actuating plunger 145 serves of course to operate the associated Bowden cable 140 to effect setup of the adding machine 11 in the manner described in detail in my aforesaid copending application.

At the time when the Bowden cables 140 have been completely actuated, the adding machine 11 is started through closure of a switch 153, Figs. 3, 10 and 11, that is operated by means connected to the rocker 105. Thus as shown in Fig. 3 of the drawings, the rocker 105 is extended downwardly as at 105A, Fig. 3, and is pivoted at 154 in the manner disclosed in the aforesaid Gollwitzer Patent No. 2,002,772. On the rear face of the portion 105A, a rearwardly extending arm 154 is secured by means including a bolt 154A,

and at its rear end, the arm 154 has an adjustable abutment screw 155 adapted to engage the operating plunger 153A, Figs. 10 and 11, of the switch 153. Such actuation of the plunger 153A at the extreme end of the downward rocking stroke of the sensing means 70 serves to close circuit to the control means of the adding machine 11 so as to initiate an adding cycle of the machine in a manner that will be described in greater detail hereinafter. Such a normal adding operation of the adding machine 11 takes place for each sensing operation of the sensing means 70.

At the time when the sensing means 70 are operated to sense the perforations 25 in a card C, the posting unit 80 is operated to print the word "Paid" in the appropriate space 17 of the posting area 15 of the card, and such operation of the posting unit is attained by means of a Bowden cable 160, as shown in Figs. 1, 3, 8 and 9 of the drawings. The Bowden cable 160 has one end of its sheath anchored in a bracket 161 that is mounted on a housing portion 40A of the machine just above the outer end of the rocker 105, and the corresponding end of the Bowden wire 160A is connected to the casting 110 by a connector fitting 162. The other end of the sheath of the Bowden cable 160 is connected, as shown in Figs. 3 and 8, to the upper wall of the posting unit by a hub 163A and a clamping screw 163 so that in the course of downward movement of the sensing means 70, the Bowden wire 160A is so actuated that the end thereof that is disposed within the posting unit 80 is moved in an upward direction, and this causes posting operation of the posting unit as will be hereinafter described.

The posting unit as herein shown comprises a pair of side plates 170 and 171 that are secured at their lower edges by screws 172 to opposite edges of a base plate 173, and the side walls 170 and 171 are connected at their upper edges by a top plate 174 that is secured to the side plates by screws 175. The forward end, that is the right-hand end as shown in Figs. 1, 3 and 8 of the drawings, is closed by an end wall 176 that is connected to the side walls 170 and 171 by screws 177. Within the housing that is thus afforded, a rocker 180 is pivoted on a transverse shaft 181, and a spring 182, acting between the rocker and its stationary transverse shaft 183, is operable to urge the left-hand end of the rocker 180 to the elevated or inactive position shown in Fig. 8. The end of the Bowden wire 160A has a connecting fitting 184 secured to the end thereof within the housing and this fitting is pivoted at 185 to the right-hand end of the rocker 180, and when the Bowden wire 160 is actuated in a downward sensing movement of the sensing means 70, the rocker 180 is moved in a counter-clockwise direction from the normal position shown in Fig. 8. In the course of such an operating movement of the rocker 180, a printing element 190 is moved from its normal elevated position shown in full lines in Fig. 8 to the operative or printing position that is shown in dotted outline in Fig. 8, and when this is done, the printing element 190 prints the word "Paid" in the appropriate space 17 in the card C, the location of the printed impression on the card C being determined by the location in which the posting unit 80 is disposed, as will hereinafter be explained in detail.

When the printing element 190 is in its elevated or inactive position shown in Fig. 8, it is

in a reversed or upwardly facing position and is in contact with a downwardly facing inking pad 191, this inking pad being carried on a rockably supported mounting block 192. This mounting block is generally square in cross section, and is held in a position where the inking pad 191 faces downwardly, as shown in Fig. 8, by a spring biased detent arm 193 that is pivoted on the transverse shaft 183 and is urged downwardly against the flat surface of the mounting bar 192 by a spring 194. When the user desires to apply ink to the ink pad 191 the mounting bar 192 may be rotated by a knurled operating handle 195 that is connected to the mounting bar 192 and is disposed outside of the side wall 170 of the posting unit. Thus the pad 191 may be faced upwardly for the application of ink thereto, and in such rotative movement of the mounting bar 192, the force of the spring 194 will be overcome and hence the retaining element 193 will be ineffective.

In the course of downward movement of the printing element 190, the position of the printing element is reversed, as will be evident by comparison of the two positions of this printing element as shown in Fig. 8, so that as the printing element approaches its lowermost position it is located in a downwardly facing relationship wherein it may effect the desired printing operation on the posting area 15 of the card C. In accomplishing such reversal of the position of the printing element 190, the printing element is supported on a mounting block 198 that is generally L-shaped in form, and this mounting block 198 has aligned shafts 199 extended from opposite ends thereof along an axis that is parallel to the printing face of the printing element 190. These shafts have reduced ends 199A that are associated with the left-hand end, Fig. 8, of the rocker 180 so that the printing element may be raised and lowered by the rocker 180, and the reduced ends 199A are also extended outwardly through generally arcuate guide slots 200 formed in the side walls 170 and 171 respectively of the housing so that the shafts 199 are guided by such slots 200 as the printing element 190 is raised and lowered. The rocker 180, as herein shown, is so formed as to afford spaced arms 180A that are disposed adjacent to the side walls of the housing where the slots 200 are formed in these side walls, and the arms 180A of the rocker 180 have slots 201 formed therein so as to extend longitudinally of such arms. The slots 201 embrace the reduced end portions 199A of the shafts 199 thereby to form the desired connection whereby the rocker 180 is effective to raise and lower the printing element 190, and nuts 204 are disposed on these shafts just inwardly of the arms 180A so as to effectually separate and guide these arms. Thus it will be clear that when the rocker 180 is moved in a counterclockwise direction from the position shown in Fig. 8, the shafts 199 will be moved downwardly along the generally arcuate path defined by the slots 200, and as this occurs the reduced ends 199A of the shafts 199 will move longitudinally in the slots 201.

The form of the slots 200 is such that the shafts 199 will first be moved in a downward and right-hand direction, and will then be moved in a downward and left-hand direction and then into vertical portions of the slots 200 until the shafts 199 reach the dotted line position shown in Fig. 8, and this path of movement of the shafts 199 is utilized in obtaining reversal of position of

the printing element 190. Thus, as will be evident in Figs. 8 and 9 of the drawings, the mounting block 198 has a slide rod 210 extended therefrom so that it projects downwardly from the block 198 when the block is in its upper position of Figs. 8 and 9. This slide rod 210 extends downwardly through a transverse bore 211 in a rocking bar 212 that is supported on a fixed horizontal axis halfway between the upper and lower positions that may be assumed by the shafts 199. The mounting for the rocking bar 212 in the present instance is attained in such a way as to afford clearance for the arms 180 and the ends 199A of the mechanism as these elements move through their operating strokes. Thus a pair of supporting brackets 215 are provided, and one of these brackets is mounted in a fixed position on each of these side walls 170 and 171. The mounting brackets are generally U-shaped in form, and one arm thereof is held in position against the outer face of the side plate by rivets 216, this arm of the member being bent outwardly at 217 to afford clearance for the adjacent end 199A of the shaft 199 that projects through the guide slot 200. At the rear or left-hand ends, Fig. 8, of the brackets 215, the material is bent in an inward direction and is then bent in a forward direction so that the other or inner arm 215A of the U-shaped bracket extends in a forward direction. The arrangement is such that the inner arm 215A of each bracket 215 is spaced from the side wall upon which it is mounted in an amount sufficient to afford clearance between the side wall and the arm 215A for the arm 180A of the rocker 180. The inner arms 215A of the brackets are utilized to afford a pivotal or rocking mounting for the rocker bar 212, and this is accomplished in the present instance by aligned pivot pins 218 that extend from opposite ends of the rocking bar 212 and through the adjacent arms 215A of the brackets 215.

With the arrangement thus described, it will be apparent that the downward movement of the shafts 199 along the path determined by the guide slots 200 serves not only to slide the rod 210 through its bearing 211, but also serves to rotate the rocking bar 212 about the horizontal axis afforded by the pivot pins 218. Hence when the rocker 180 has moved through substantially one-half of its counterclockwise rocking stroke from the position shown in Fig. 8, the slide rod 210 will be located in a substantially horizontal position, and the printing element 190 will be faced in a forward or right-hand direction as viewed in Fig. 8. Continued downward movement of the shafts 199 serves to complete the reversal of position of the printing element 190 so that when the shafts 199 reach the lower limit of their travel, the printing element 190 will be disposed in the downwardly facing position shown in dotted outline in Fig. 8, and it is while the printing element is in this position that the desired impression is made on the card C. Upon reversal of movement of the rocker 180, the position of the printing element 190 is again reversed and the printing element is brought into its upper or rest position in engagement with the ink pad 191.

It has been pointed out hereinbefore that the printed impression 22 that is made upon the card C by the posting unit 80 is formed in a particular one of the spaces 17 of the card in accordance with the location of the posting unit 80 with respect to the operating position in which the card C is located by the stop finger 139, and

in accordance with the present invention, the posting unit 80 may readily be set or located on the table top T of the machine so as to attain the desired location of the printed impression 22 on the card C. In attaining this result, the posting unit has a pair of fastening bolts 220 extended downwardly through the top wall 174, and the reduced lower ends of the bolts 220, as indicated at 221 in Fig. 8, are extended through openings formed in the base plate 173 of the posting unit. The shoulders formed on the fastening bolts 220 above the reduced portions 221 thereof are arranged to seat against the upper face of the base plate 173 and the screw threaded lower ends of the reduced portions 221 are adapted to be threaded into selected screw threaded openings 224 that are formed in a mounting plate 225 that is secured on the table top T of the machine. In the present instance the mounting plate 225 is secured in position on the table top T by cap screws 226 that extend through slots 227 formed in the plate 225, these slots being extended transversely with respect to the path of movement of the card C so that the plate 225 may be accurately located transversely with respect to the sheet guideway G. In forming and locating the threaded mounted openings 224 in the mounting plate 225, the arrangement or disposal of these openings 224 is correlated with the arrangement of the columns 16 and the spaces 17 in the posting area 15 of the card C. Thus where the card C has five columns, the mounting plate 25 is formed with six vertical columns of threaded openings 224, and the spacing of these columns is exactly the same as the width of the columns 16. Thus the two fastening bolts 220 are also spaced apart in an amount equal to the width of each of the columns 16, and with this arrangement, five different transverse locations of the posting unit 80 may be attained that correspond with the locations that will be assumed by the different columns 16 when the card C is stopped at the operating position of the machine by the stop finger 60.

It will also be observed that in each column of openings 224 the present embodiment of the invention provides twelve such openings that are spaced from each other in an amount equal to the line spacing dimension of the spaces 17 on the card C. Thus the mounting screws or bolts 220 may be engaged with the openings 224 in any selected one of the twelve lines of openings in accordance with the month for which the posting operation is being performed. Hence the selection of openings 224 with which the mounting bolts 220 are associated determines or selects not only the column 16 in which the posting impression 22 is to be made, but also determines or selects the spaces 17 of the selected column in which such impression is to be made. Such selection of course is in practice applicable to a complete and relatively long run of the machine so that when posting operations are to be performed for a particular month, the selection and mounting of the posting unit 80 in a particular position serves to locate the posting impressions 22 in the proper location on the cards for the entire run of the machine.

It will be observed in Figs. 3 and 8 of the drawings that rearwardly of the base plate 173, the lower edges of the side plates 170 and 171 are offset upwardly as at 228, thereby to assure adequate clearance between these plates and the surface of the table top T. It should also be observed that in the course of adjusting movement of the

posting unit 80 in a front to rear direction, the operator must avoid the making of impressions directly over the belt 38, and hence after the posting unit has been adjusted to a particular relationship, the belt 38 may be disposed in a lateral position wherein it will be spaced substantially from the location at which the impression is to be made by the printing element 190. Proper clearance for such adjustment of the belt 38 is afforded by the slot 67 in the lower edge of the stop finger plate 61, and it will be recognized of course that the pressure rollers 73 will in such an instance be adjusted to proper positions laterally of the guideway G by the adjusting mechanism 229 that is indicated generally in Fig. 3 of the drawings.

Since the posting operations that are performed by the present machine constitute a part of an accounting procedure, it is desirable to afford a constant check on the operations of the machine, and as one means for enabling this to be done, a visual counter 230 is mounted on the housing 40A immediately above the rocker arm 105, and the counter 230 has an operating arm 231 that is connected by a link 232 to the casting 110. With this arrangement, each operation of the sensing means 70 serves to actuate the counter 230 and thus the number of cards C that have been sensed by the sensing means 70 is visually indicated by the counter 230 at all times.

As another means for affording a ready check upon the accounting operations performed by the present machine, means are provided for taking a total in the adding machine 11 each time a predetermined number of cards C have been passed through the machine. Such a total may, if desired, constitute a group total relating to the total of the amounts sensed from the particular group of cards C and when such a group total is taken, only the primary accumulator of the adding machine 11 is cleared, leaving the grand total accumulator of the adding machine with the running total standing therein. In order that the adding machine 11 may operate through such a total operation, the machine 10 is stopped whenever such a total operation is to be performed, and means are provided for counting the number of cycles of operation of the machine 10 and for stopping the machine 10 and initiating a total operation of the adding machine 11 each time a predetermined number of cards C have been passed through the machine. Thus, as shown in Figs. 1, 3, 10 and 11, a counting mechanism 240 is mounted on an end wall of the housing 40A so as to be actuated by the machine 10 each time the machine operates through a complete cycle. In the present instance the counting mechanism 240 is in the nature of a ratchet mechanism that is shown in detail in Figs. 10 and 11. This ratchet mechanism includes a ratchet wheel 241 having a mounting hub 242 whereby the ratchet wheel is supported on a stub shaft 243. This stub shaft 243 is carried on the vertical arm 244 of a mounting bracket 245, this mounting bracket 65 being L-shaped in character and providing a horizontal arm 246 extending to the right in Fig. 10, and upon which a pair of normally open switches 247 and 248 are mounted. The bracket 245 also serves as a support for the microswitch 153, which is secured to the left face of the vertical portion of the bracket by screws 153B. On the end of the stub shaft 243, a rocker 250 is mounted and held in place by friction plate 251A that is urged into contact with the rocker 250 by a spring 251. Nuts 252 threaded onto the

reduced end of the stub shaft 243 serve to hold the spring 251 in place on the stub shaft 243. The rocker 250 has a pawl 255 pivoted thereon as at 256 and having the pointed end thereof yieldingly urged into contact with the teeth of the ratchet wheel 241 by a spring 255A acting between the pawl 255 and the laterally bent flange 250A formed on the rocker 250. The rocker 250 has one end of a link 257 pivoted thereto, and the other end of the link 257 is pivoted on the end of the shaft 243 by a pivot 258 that is located eccentrically with respect to the rotative axis of the shaft 40. The eccentricity of the pivot 258 is such that in each rotation of the shaft 40, the ratchet wheel 241 is advanced in an amount equal to the spacing of the teeth 241A thereof, and the ratchet wheel 241 is held against retrograde movement by the friction plate 251A. The number of teeth 241A that are thus provided on the ratchet wheel 241 is equal to the number of cards C that are to be passed through the machine for each total operation of the adding machine 11, and in the present case the ratchet wheel 241 has fifty teeth so that a total is taken by the adding machine 11 and is printed on the tape 11A thereof for each fifty cards C that are passed through the machine.

The control of the total operation of the adding machine 11 and the stopping of the machine 10 by the counter 240 are attained by the switches 247 and 248, and means are associated with the ratchet wheel 241 for closing the switches 247 and 248 when the ratchet wheel 241 has completed a full revolution. Thus as will be evident in Figs. 10 and 11, the sleeve 242 upon which the ratchet wheel 241 is mounted has a switch operating arm 260 fixed thereon and so as to extend radially therefrom, and this arm 260 has a tooth 260A formed at the end thereof in position to engage a cam surface 261 that is provided on a resilient operating arm 262 disposed immediately above the upper blade of the switch 248. Thus when the flexible operating arm 262 is bent downwardly due to the engagement of the cam surface 261 by the tooth 260A, the switch 248 is closed, and at this same time, an insulating lug 263 provided on the end of the operating arm 262 engages the extended end of the upper blade of the switch 247 so as to impart similar closing movement to the switch 247. Such closure of the switches 247 and 248 occurs prior to the completion of a particular cycle of operation of the machine 10, and as an incident to such closure, electrically operable means are energized that serve to stop the machine 10 at the end of the cycle and which serve to initiate a subtotal or group total operation of the adding machine 11 when the adding machine has completed the cycle in which it is then operating. The total operation of the adding machine 11 is instituted when a control solenoid 285, Fig. 11, of the adding machine 11 is energized, the manner in which the solenoid 265 operates in initiating such a total operation being described in detail in my copending application Serial No. 676,329, filed June 12, 1946. In Fig. 11 of the drawings, the appropriate total control solenoid 265 of the adding machine 11 is shown in diagrammatic association with the switch mechanism, and as there shown, a wire 266 extends from one terminal of the solenoid to the lower blade of the switch 247. Wires 267 and 268 in series extend from the other terminal 5 of the solenoid 265 to one terminal of a battery 75

269, while wires 270 and 271 extend in series from the other terminal of the battery 269 to the upper contact of the switch 247. Thus an energizing circuit is afforded for the solenoid 265 and this circuit is completed so as to initiate a total cycle of the adding machine when the switch 247 is closed by the counter 240. The other switch 248 serves to control the stopping of the machine 10, and for this purpose, an operating solenoid 275 is mounted on the frame of the machine 11 adjacent to the stop lever 43, and the armature 276 of the solenoid 275 is pivotally connected to the stop lever 43 as indicated at 277 in Fig. 11. Thus when the solenoid 275 is energized, the stop lever 43 is actuated in a counterclockwise direction so as to disengage the clutch means that serve to connect the flywheel 41 to the operative mechanisms of the machine 11. The clutch means that are thus disconnected are of the one-revolution type, as described in the aforesaid Gollwitzer Patent No. 2,002,772, so that the mechanism driven thereby comes to rest in a predetermined relationship which constitutes the end of the operating cycle of the machine 11. The solenoid 275 has one terminal thereof connected by a wire 279 to the juncture of the wires 267 and 268, while a wire 281 extends from the other terminal of the solenoid to the upper contact of the switch 248. The lower contact of the switch 248 is connected by a wire 283 to the wire 270 so that an energizing circuit is provided for the solenoid 275 and this circuit is completed when the switch 248 is closed.

With the arrangement that has thus been described, the counter 240 operates after fifty cards C have been passed through the machine to close the switches 247 and 248 and such switch closure causes the solenoids 265 and 275 to be energized. The solenoid 275 serves to operate the stop lever 43 of the machine 11 thereby to stop operation thereof, while the solenoid 265 causes a total cycle of the adding machine 11 to be instituted. As soon as this total operation has been performed, the operator may again shift the start lever 42 so as to cause operation of the apparatus to be resumed.

It has been pointed out hereinbefore that the microswitch 153 is closed in each operation of the sensing means 70 after set-up of the adding machine 11 has been completed so as to cause the adding machine to operate through an adding cycle, and this is effected by operative association of the switch 153 with a starting solenoid 285, Fig. 11, that constitutes the starting solenoid of the adding machine as set forth in my aforesaid copending application Serial No. 676,329, filed June 12, 1946. Such association of the switch 153 with the solenoid 285 is afforded by circuit including a wire 286 extended from the wire 268 to one terminal of the solenoid 285, and a wire 287 extended from the other terminal of the solenoid to one contact of the switch 153, as shown in a diagrammatic way in Fig. 11. A wire 288 extends from the other contact of the switch 153 to the wire 283, thereby providing an energizing circuit that is closed by the switch 153 in each operation of the sensing means 70.

It will be recognized that when the supply of cards C is exhausted, or when such cards become jammed in the sheet guideway, or when a card is not properly positioned at the operating position for any other reason, it is desirable that sensing operation of the sensing means 70 and the related operation of the adding machine 11

should not take place, and in the present apparatus such undesired operation is prevented by sheet safety means that are effective to prevent a succeeding cycle of machine operation when a card C is not detected in the operating position at the proper time near the close of a particular cycle. Such sheet safety means are effective in each cycle of machine operation to sense the presence or absence of a card at the operating position shortly after the time when such a card should arrive at such position, and in the event that absence of a card is detected the stop solenoid 275 is energized so as to stop the machine at the end of the cycle in which it is then operating.

Thus, as shown in Figs. 1, 2, 3 and 11, a detecting finger 290 is mounted on the shaft 64 so that a downwardly projecting finger 290A on the forward end thereof is adapted to engage a card C in the operating position near the forward edge 21 of the card. The finger 290 is urged in a downward or detecting direction by a spring 291, and such movement is governed by a cam 292 fixed on the stop finger cam shaft 44, the cam 292 being engaged on its lower edge by a cam roller 293 carried on the rearwardly projecting end of the detecting finger 290. The cam 292 is so timed and related to the operation of the sheet feed means 37 and the stop finger 60 that the detecting finger 290 is moved downwardly through a detecting stroke late in each machine cycle and after the time when a card C should be located at the operating position. In the event that a card C is located at the operating position the detecting finger 290A comes to rest momentarily on the upper surface of the card C, but if such a card is not present, the finger 290A continues its downward movement through an opening 296 in the table top T. When this occurs, the finger 290A engages and closes a normally open switch 297 that is disposed beneath the opening 296, and such switch closure causes the stop solenoid 275 to be energized. Thus, as shown in Fig. 11, the switch 297 has a wire 298 extended from one contact thereof to the wire 281, while a wire 299 extends from the other contact of the switch 297 to the wire 270, and this affords an energizing circuit for the stop solenoid 275 that is under control of the switch 297. It will be noted in this connection that the closure of the switch 297 when a card C is not detected takes place a sufficient time before the end of the cycle to enable the resulting operation of the stop lever 43 and the associated one-revolution clutch mechanism to stop the machine at the end of the cycle that is then in progress.

Through this arrangement the absence of a card C at the operating position causes the operation of the machine to be stopped in such a manner that the proper counting action of the counter 240 is assured and improper or false operation of the adding machine 11 is avoided.

From the foregoing description it will be apparent that the present invention materially simplifies the production of posted records, particularly where such posted records relate to a regular amount that is to be deducted or applied to some specific purpose at regular periods. It will also be apparent that the amounts that are thus represented in the posting operation may under the present invention be sensed and accumulated at the time when the posting operation is being performed, and hence a rapid performance of the desired work is accomplished under this invention. The apparatus of the present invention also as-

sures proper location of the sheets or record cards with respect to the sensing mechanism, thereby assuring that the proper amounts are introduced into the accumulator. Moreover, the apparatus of the present invention enables the posting unit to be readily set in different positions so as to perform the posting operation upon different areas of the record cards, and the arrangement is such that this shifting or setting of the posting unit may be accomplished without material disturbance of the means that operate the posting unit. Through the use of the present invention, posted records of the amounts that are to be deducted from at least certain of a group of payroll checks may be readily prepared, and the accounting operations may be verified by the accumulated totals that are produced in the course of operation of the present machine.

Thus, while I have illustrated and described the preferred embodiment of my invention, it is to be understood that this is capable of variation and modification and I therefore do not wish to be limited to the precise details set forth, but desire to avail myself of such changes and alterations as fall within the purview of the following claims.

I claim:

1. In a machine of the character described, a frame affording a table top, a sheet guideway extended along said table top, means for separating and feeding sheets into said sheet guideway at one end thereof, means for advancing such a sheet along said sheet guideway, stop finger means adapted to be disposed in an operative position to stop the movement of such a sheet with the sheet disposed in a predetermined operating position in said sheet guideway, means for sensing data representations in such a sheet while the sheet is located in said operating position, printing means for making a printed posting impression on a predetermined area of such a sheet while such a sensing operation is being performed by said sensing means, accumulator mechanism set up under control of said sensing means and rendered operative to perform an accumulating operation when said accumulating mechanism has been set up by said sensing means, means for counting the number of sensing operations of said sensing means, and means associated with said counting means and operable when a predetermined number of sheets have been passed through the machine to institute a total operation of said accumulator and also operable to stop operation of said sheet feeding, sensing and printing means.

2. In a machine of the character described, a frame affording a table top, a sheet guideway extended along said table top, means for separating and feeding sheets into said sheet guideway at one end thereof, means for advancing such a sheet along said sheet guideway, stop finger means adapted to be disposed in an operative position to stop the movement of such a sheet with the sheet disposed in a predetermined operating position in said sheet guideway, means for sensing data representations in such a sheet while the sheet is located in said operating position, printing means for making a printed posting impression on a predetermined area of such a sheet while such a sensing operation is being performed by said sensing means, accumulator mechanism set up under control of said sensing means and rendered operative to perform an accumulating operation when said accumulating mechanism has been set up by said sensing means, and means

operable when a predetermined number of sheets have been passed through the machine to stop operation of said sheet feeding, sensing and printing means, and to initiate a total taking operation of said accumulator.

3. In a machine of the character described, a frame affording a table top, a sheet guideway extended along said table top, means for separating and feeding sheets into said sheet guideway at one end thereof, means for advancing such a sheet along said sheet guideway, stop finger means adapted to be disposed in an operative position to stop the movement of such a sheet with the sheet disposed in a predetermined operating position in said sheet guideway, means for sensing data representations in such a sheet while the sheet is located in said operating position, printing means for making a printed posting impression on a predetermined area of such a sheet while such a sensing operation is being performed by said sensing means, and accumulator mechanism set up under control of said sensing means and rendered operative to perform an accumulating operation when said accumulating mechanism has been set up by said sensing means.

4. In a machine of the character described, a frame affording a table top, means for separating and feeding sheets one at a time into a predetermined operating position on said table top, means for sensing data representations in such a sheet while the sheet is located in said operating position, accumulator mechanism set up under control of said sensing means and rendered operative to perform an accumulating operation when said accumulating mechanism has been set up by said sensing means, and means for making a printed posting impression on a predetermined area of such a sheet while such a sensing operation is being performed by said sensing means.

5. In a machine of the character described, a frame embodying a table top, means affording an operating position on said table top, means for feeding sheets one at a time into said operating position, means for sensing data representations in said sheet while it is located at said operating position, means for printing a posting impression on such a sheet in a predetermined area thereof an indication that such data representations have been sensed, and means for accumulating the amounts sensed by said sensing means.

6. In a machine of the character described, a frame affording a table top, means for separating and feeding sheets into a predetermined operating position on said table top, means for sensing data representations in such a sheet while the sheet is located in said operating position, print-

ing means for making a printed posting impression on a predetermined area of such a sheet while such a sensing operation is being performed by said sensing means, accumulator mechanism set up under control of said sensing means and rendered operative to perform an accumulating operation when said accumulating mechanism has been set up by said sensing means, and means for changing the operative relationship of said posting unit with respect to said operating position to thereby change the location of the printed impression formed thereby on a sheet located in said operating position.

7. In a machine of the character described, a frame embodying a table top, means affording an operating position on said table top, means for feeding sheets one at a time into said operating position, means for sensing data representations in said sheet while it is located at said operating position, means for printing a posting impression on such a sheet in a predetermined area thereof as an indication that such data representations have been sensed, means forming an operating connection between said sensing means and said posting means to operate said posting means each time said sensing means are operated, and means for accumulating the amounts sensed by said sensing means.

WALTER T. GOLLWITZER.
